UNITED STATES PATENT OFFICE.

EDWARD C. HEIMLICH, OF DETROIT, MICHIGAN, ASSIGNOR OF ONE-HALF TO JOHN H. KENNEDY, OF DETROIT, MICHIGAN.

SMOKE-CONSUMER.

1,120,484.

Specification of Letters Patent.

Patented Dec. 8, 1914.

Application filed April 1, 1914. Serial No. 828,665.

To all whom it may concern:

Be it known that I, EDWARD C. HEIMLICH, a citizen of the United States of America, residing at Detroit, in the county of Wayne 5 and State of Michigan, have invented certain new and useful Improvements in Smoke-Consumers, of which the following is a specification, reference being had thereto to the accompanying drawings.

This invention relates to a smoke consumer particularly designed for furnaces to cause or facilitate the consumption of the smoke and gases or products of combustion, and thus more perfectly utilize the fuel, 15 while at the same time avoid the many evils attending the discharge of such products directly into the atmosphere.

The invention consists, essentially, in an arrangement of air and steam forcing devices by which smoke and gases are repeatedly carried into the fire box or combustion chamber of a boiler furnace, thus permitting of unburnt products of combustion being consumed to increase the efficiency 25 of a boiler furnace. The steam and air injectors are arranged so as not to interfere with the firing of a boiler furnace, the use of flue blowers or other boiler accessories, and provision is made whereby the operation 30 of the smoke consumer can be easily controlled.

Reference will now be had to the drawings, wherein—

Figure 1 is a front elevation of a boiler 35 furnace provided with a smoke consuming apparatus; Fig. 2 is a longitudinal sectional view of a portion of the same taken on or about the line II—II of Fig. 1, looking in the direction of the arrow; Fig. 3 is an enlarged longitudinal sectional view of a combined air and smoke injector, and Fig. 4 is a similar view of a combined air and steam injector.

In the drawings there is illustrated a conventional form of boiler furnace embodying a front or setting 1, a bridge wall 2, a grate 3, a combustion chamber or fire box 4, a flue 5, boiler doors 6 and fuel doors 7.

Mounted in the front or boiler setting 1, 50 above the fuel doors 7, are angularly disposed or downwardly directed nozzles 8 having the outer ends thereof provided with four-way connections 9 supporting air intake funnels 10 that longitudinally align 55 with the nozzles 8. The four-way connec-

tions 9 have detachable caps or stuffing boxes 11 for the branch pipes 12 of a main steam supply pipe 13 suitably supported in front of the boiler setting 1. The inner ends of the branches 12 are provided with elbows 14 and jets 15, said jets extending longitudinally of the nozzles 8 and concentrically thereof to support flared nipples 16 approximately intermediate the ends of the nozzles. The main steam pipe 13 has a conventional 60 form of valve 17 for controlling the supply of steam to the nozzles 8 and the combustion chamber or fire box 4 of the boiler furnace.

The four-way connections 9 are provided 70 with smoke and gas inlet pipes 18 that extend upwardly in front of the boiler setting 1 and into the space between the boiler doors 6 and the flue sheet of the boiler 5, the inner ends of said pipe having funnel or dome-shaped mouth pieces 19 adapted to gather and direct smoke and gases from the flues of the boiler 5 into the pipe 18 and into the nozzles 8; the suction produced by the steam injectors within the nozzles tending to draw 80 the air, smoke and gases into the nozzles where the steam, air, smoke and gases thoroughly commingle and are injected into the combustion chamber or fire box 4, whereby the unburnt products of combustion can be 85 consumed. The injection of steam carries the smoke and gases to a point in proximity to the bridge wall 2, which serves as a baffle and produces eddies of smoke and gas that are subjected to the action of the fire upon 90 the grate 3, before escaping to again pass through the flues of the boiler 5 and to a stack or chimney.

To increase the combustion of coal or other fuel within the combustion chamber 95 or fire box, nozzles 20 are mounted in the boiler setting 1, between the fuel doors 7. These nozzles have three-way connections 21 supporting air intake funnels 22 in longitudinal alignment with the nozzles 20. 100 The three-way connections 21 have detachable caps or stuffing boxes 23 and extending therethrough are the branches 24 of a branch steam pipe 25 connected to the main steam supply pipe 13, as best shown in Fig. 1. 105 The branch pipes 24 have the inner ends thereof provided with small three-way connections or T's 26 supporting jets 27 concentrically of the nozzles 20. The T's 26 also support caps 28 and 29 and extending 110

through said caps and longitudinally of the jets 27 are valve rods 30. These rods have large exteriorly screw threaded portions 31 in screw threaded engagement with the caps 28, and the outer ends of said valve rods have hand wheels 32, while the inner ends thereof are provided with valves 33 adapted to engage in seats 34 provided therefor in the ends of the jets 27.

10 Air and steam can readily commingle in the nozzles 20 as the air and steam are injected into the combustion chamber or fire box 4 to impinge the bridge wall 2 and be baffled to that extent as to thoroughly commingle with the steam, smoke and gases injected by the nozzles 8. In this manner a fire within the combustion chamber is materially enlivened, the products of combustion thoroughly consumed, and should any products of combustion escape a large percentage of the same are collected and returned to the combustion chamber for ignition.

15 It is through the medium of the adjustable valves 33 that the steam can be shut off to the combined air and steam injectors, whereby air will be simply drawn into the combustion chamber or fire box 4. With all four injectors in operation, the steam to the same can be controlled by the valve 17. With the 20 steam shut off, there is still a draft from the front end of the flue boiler through the pipes 18 to the nozzles 8, drawing in cold air, and both the cold and hot air tend to increase combustion in the fire box.

25 While in the drawing there is illustrated

a preferred embodiment of my invention, it is to be understood that the structural elements are susceptible to such changes, as in the size, shape and manner of assemblage, as fall within the scope of the appended claim.

What I claim is:

30 In a smoke consuming apparatus, the combination with a boiler furnace having a boiler setting, a bridge wall, a fire box, a boiler, and a steam supply pipe, of combined air, smoke and steam injectors angularly disposed in the boiler setting and in communication with said steam supply pipe, and adapted to discharge air, smoke and steam upon fuel in said fire box; combined steam and air injectors mounted in the boiler setting in communication with said steam supply pipe and adapted to discharge air and steam into the fuel in said fire box and coöperate with the first mentioned injectors in discharging air, steam and smoke in proximity to the bridge wall of said furnace, means arranged in front of said boiler for conveying smoke and gases to the first mentioned injectors, and outwardly seating valves at the inner ends of the last mentioned injectors for controlling the supply or steam thereto.

35 In testimony whereof I affix my signature in presence of two witnesses.

EDWARD C. HEIMLICH.

Witnesses:
